CLAIM

The ornamental design for a travel documents holder, as shown and described.

DESCRIPTION

FIG. 1 is a front view of the travel documents holder of the invention;

FIG. 2 is a top plan view of the travel documents holder of the invention;

FIG. 3 is a left side view of the travel documents holder of the invention;

FIG. 4 is a right side view of the travel documents holder of the invention;

FIG. 5 is a back view of the travel documents holder of the invention;

FIG. 6 is a bottom view of the travel documents holder of the invention; and,

FIG. 7 is a perspective view of a partially folded travel documents holder of the invention.

The dashed lines shown in all views represent stitching and are part of the claimed design.

UNITED STATES PATENT AND TRADEMARK OFFICE
CERTIFICATE OF CORRECTION

PATENT NO. : Des. 543,359 S
APPLICATION NO. : 29/232134
DATED : May 29, 2007
INVENTOR(S) : Massimo Suppancig

Page 1 of 1

It is certified that error appears in the above-identified patent and that said Letters Patent is hereby corrected as shown below:

On Title page

Item 73

Correcting the Assignee name to read --Valextra S.p.A.-- instead of "Valextra S.R.L."

Signed and Sealed this

Twentieth Day of May, 2008

JON W. DUDAS
Director of the United States Patent and Trademark Office
